DESIGN FOR A COMBINED FLAG AND STAFF

Abraham Samuel Rosen, New York, N. Y.

Application July 28, 1938, Serial No. 78,788

Term of patent 7 years

To all whom it may concern:

Be it known, that I, Abraham Samuel Rosen, a citizen of the United States, residing at 56 Jewel St., in the city of New York, county of Kings, and State of New York, have invented a new, original, and ornamental Design for a Combined Flag and Staff, of which the following is a specification, reference being had to the accompanying drawing, forming part thereof.

The figure is a front elevational view of a combined flag and staff, showing my new design.

My design is characterized by a flag comprising a field of blue having the "Shield of David" in the upper left corner, the "Lion of Judah" in the lower left corner, and a rectangle in the upper right hand corner, said rectangle containing representations of twelve semiprecious stones, each representing a tribe of Israel.

I claim:—

The ornamental design for a combined flag and staff, as shown and described.

ABRAHAM SAMUEL ROSEN.
